UNITED STATES PATENT OFFICE

PAUL DIETERLE, OF BINGHAMTON, NEW YORK

MEANS FOR FRAMING PICTURES

Application filed October 27, 1931. Serial No. 571,421.

My invention relates to a means and method for framing pictures and has for its primary object the provision of a simple inexpensive framing arrangement for photographs, prints, specimens, and the like which seals the same from dust, dirt or other foreign matter which often filters through the known framing devices and mars or discolors the picture.

10 Another object of my invention lies in the provision of a framing means and method which can be easily and quickly accomplished by unskilled persons whereby favorite pictures and prints can be preserved in 15 proper condition.

Other objects and advantages will appear as the description proceeds, reference now being had to the figures of the accompanying drawing forming a part of this application 20 and wherein like reference numerals indicate like parts.

In the drawing:

Figure 1 is a full front plan view of a picture framed in accordance with my invention.

Figure 2 is a rear view thereof, certain parts being broken away for clearness of illustration.

Figure 3 is a detail sectional view taken on 30 the line 3—3 of Figure 1 and illustrating the method of assembly of the frame.

Heretofore in framing pictures, prints, specimens, and the like, no adequate means has been provided for effectively sealing the 35 framed element from the filtering of dust, dirt, etc. around the frame portions and on to the face thereof. Also the attempted "home framing" by unskilled persons, which has heretofore been practiced, has been unsatisfactory because no simple method was known by which the framing could be completed economically, easily and quickly. The use of glue, paste, and even of water soluble adhesive tape or strips, has made such 40 practice an inconvenient and "messy" one and often has resulted in spoiled pictures.

In carrying out my invention, and in overcoming these difficulties, I have provided a 45 backing member 1, of substantial thickness and it may be of any suitable or desired ma-

terial such as heavy seasoned cardboard or the like, and which is not subject to ready buckling or distortion. A similar front piece or frame member 2 is also provided, of the same size as the backing member 1, but provided with the central cut out portion 3 through which the framed member may be viewed. Of course, the color and design of this front framing member 2 is optional and depends upon taste, harmony with the member to be framed, etc.

55 The transparent cover member for closing the opening 3 in the front piece 2 and by which the print, photograph, specimen, or other element 4 is to be framed, is preferably a cellulosic sheet 5 of non-inflammable or of at least slow burning characteristics, such as acetyl cellulose sheets. Glass, of course, may be used for this purpose but because 60 of the flexible and nonbreakable character of the cellulose material, it is preferred.

65 In assembling these parts in the form of a frame or mount, I make use of an adhesive tape material, the adhesive portion of which is gumlike and water insoluble. Such tape 70 is clean, easy to apply, and forms an effective seal against dust, dirt, etc. as will hereinafter be explained. This tape is indicated in the drawing by the reference character 6, in one position of its use and 7 in another 75 position of its use.

80 In carrying out my improved method of mounting prints or the like, the front member 2 is placed face downwardly on a suitable support and the transparent covering 5 is then laid thereon in a position to overlie the opening 3. The print or element 4 to be framed is then laid upon the transparent cover 5 in proper alignment and position 85 with respect to the opening 3. This member 4 is preferably first trimmed so as to be slightly smaller in size than the transparent cover 5, the cover plate having also been trimmed to be of smaller size than the front plate 2.

90 With the parts assembled in this position, strips of the adhesive tape 6 are placed along the edges of the assembled members whereby to secure them together and tightly to the rear side of the front piece 2. This is clearly 95 illustrated in Figure 3 from which it will 100

be noted that the tape 6 is pressed into tight adhesive contact with the elements 4, 5 and 2, overlapping each of the surfaces to be secured tightly thereto and thus forming an effective seal against dust, dirt, etc. reaching the back side of the transparent cover 5 and the print or other element 4 to be framed. This taping and sealing is provided completely around the side edges of these elements and then the back piece 1 is laid thereover and bound into tight engagement therewith by the strips 7 of adhesive embracing all the outside edges of the front and back members 1 and 2.

15 This outside binding strip 7 provides in addition to a binding means for the mount, a border around the face of the frame and of course, may be of any desired or selected color or design.

20 Furthermore, this binding strip 7 provides an additional effective seal against the entry of dirt, dust, etc. to the framed element 4. It will thus be seen that by this means and method I have provided a mount which is attractive in appearance, economical in cost, and very easily and conveniently assembled, and which because of its novel arrangement of parts permanently preserves and protects the framed element.

25 30 Of course, changes may be made in details without departing from the spirit and scope of my invention. I do not limit myself, therefore, to the exact form and arrangement of strips herein described other than by the appended claims.

I claim:

40 1. A framing device comprising a front member having an opening, a transparent covering member overlying said opening on the rear side of said front member, an element to be framed overlying said covering member, adhesive strips engaging said element, covering member and front member around their edges whereby all of said members are sealed together, said cover member being of less dimensions than the front member and said element being of less dimensions than said cover member whereby said tape engages directly all of said members; a backing member overlying all of said members and adhesive strips sealing the edges of said front and backing members together, said adhesive strips being water insoluble.

45 50 2. A framing device comprising a front member having an opening, a transparent covering member overlying said opening on the rear side of said front member, an element to be framed overlying said covering member, and adhesive strips engaging said element, covering member and front member around their edges whereby all of said members are sealed together; a backing member overlying all of said members and adhesive

55 60 65 strips sealing the edges of said front and backing members together.

3. A framing device comprising a front member having an opening, a transparent covering member overlying said opening on the rear side of said front member, adhesive

strips engaging said element, covering member and front member around their edges whereby all of said members are sealed together, said cover member being of less dimensions than the front member and said element being of less dimensions than said cover member whereby said tape engages directly all of said members, a backing member overlying all of said members and adhesive strips sealing the edges of said front and backing members together.

4. A framing device comprising a front member having an opening, a transparent covering member overlying said opening on the rear side of said front member, an element to be framed overlying said covering member, adhesive strips engaging said element, covering member and front member around their edges whereby all of said members are sealed together, said cover member being of less dimensions than the front member and said element being of less dimensions than said cover member whereby said tape engages directly all of said members, a backing member overlying all of said members and adhesive strips sealing the edges of said front and backing members together, said adhesive strips being water insoluble.

5. A framing device comprising a front member having an opening, a transparent covering member overlying said opening on the rear side of said front member, an element to be framed overlying said covering member, adhesive strips engaging said element, covering member and front member around their edges whereby all of said members are sealed together, said cover member being of less dimensions than the front member and said element being of less dimensions than said cover member whereby said tape engages directly all of said members; a backing member overlying all of said members and adhesive strips sealing the edges of said front and backing members together, said adhesive strips being water insoluble, and said transparent covering being of substantially uninflammable cellulosic material.

In testimony whereof, I affix my signature.

PAUL DIETERLE.
